(57) **CLAIM**

The ornamental design for a nozzle for pressure washer, as shown and described.

DESCRIPTION

FIG. 1 is a top perspective view of a nozzle for pressure washer showing my new design.

FIG. 2 is front view thereof;

FIG. 3 is a rear view thereof;

FIG. 4 is a side view thereof;

FIG. 5 is an opposite side view thereof;

FIG. 6 is a top plan view thereof;

FIG. 7 is a bottom plan view thereof; and,

FIG. 8 is a view of the nozzle for pressure washer shown connected to a lance of a pressure washer.

The broken lines shown in FIGS. 1 and 6 illustrate portions of the nozzle for pressure washer that form no part of the claimed design. The broken lines in FIG. 8 showing the lance connected to the nozzle for pressure washer illustrate the environment of the claimed design and forms no part thereof.

1 Claim, 2 Drawing Sheets
